Application August 3, 1940, Serial No. 350,215

11 Claims.

(Cl. 242—43)

This invention relates to the manufacture of thread or yarn and more particularly to a process of and apparatus for preparing bodies of such material in package form.

While wound packages of thread are employed incident to many industrial operations, one of the chief uses of such packages at this time is in conjunction with the manufacture of rayon by the bobbin spinning process.

In the manufacture of rayon according to the bobbin spinning process, freshly formed filaments are led directly from a spinning bath to a spinning bobbin on which they are wound in successive layers until a package of suitable size has been prepared. Ordinarily the bobbin is rotated and the yarn is laid up thereon in longitudinal courses by a traverse mechanism. Rayon yarn, after having been so prepared in package form is not yet, however, in finished condition, but must be later subjected to a number of after-treatments such as washing, desulphurizing, bleaching and drying. According to conventional practice these after-treatments are accomplished while the yarn is still in package form as originally wound on the bobbin, a hollow perforated spinning bobbin being employed so that the package of yarn may be placed in either a pressure or vacuum system in which treating liquids are forced radially through the perforations in the bobbin and through the yarn body wound thereon.

The process outlined above has proved somewhat satisfactory in operation, and is now in commercial use. It has been found, however, that yarn produced according to the process is at least partially imperfect, giving evidence of not having been subjected, in a uniform manner, to the customary after-treatments employed in the preparation of high quality rayon.

After extensive study and experimentation, it was determined that the difficulty in contacting, to a uniform extent, all of the component yarn on a spinning bobbin with the necessary after-treating liquids arose chiefly because of the density of the wound package, some portions of the package being so dense as to materially inhibit the passage of treating liquids therethrough.

In an effort to overcome the foregoing difficulty a number of processes and apparatus have been developed. Quick shifting of the traverse arm, for example, was found to be of importance in avoiding too much density of the package at the ends, while a stroke displacement auxiliary to ordinary stroke shortening has been partially successful in producing a washable package.

With the advent of high tension yarns, however, the prior art efforts at solving the washing problem were wholly unsuccessful, the additional tension serving to greatly increase the density of the package.

When the new problems incident to high tension yarn were first discovered it was thought that the synchronism of the traverse arm with the spinning bobbin to produce a pattern wind of the type commonly known to the industry as the "basket weave" would offer a satisfactory solution. The "basket weave" package, however, cannot be treated satisfactorily because the interstices between adjacent layers of yarn present a radial opening from the periphery of the package to the bobbin. Treating liquids, in following the line of least resistance in their passage through the yarn body, are thus ejected through these interstices, consequently by-passing much of the yarn body that should be subjected to treatment. Again the result was a final product lacking in uniformity.

Another suggested remedy for preparing a package having good washing qualities was the employment of a bobbin and traverse driven independently, thus reverting to the old type of dense package, the size of the package being considerably reduced in diameter. While it is possible to produce bobbins so wound which will respond satisfactorily to treatment, the small size of each package so reduces operating efficiency as to render this plan wholly unsatisfactory from an economic standpoint.

It is therefore an object of this invention to overcome all of the foregoing difficulties and to produce wound thread packages having superior washing qualities regardless of the tension to which the yarn may be subjected during spinning, or of the size of the package ultimately produced.

In accordance with the concept of the present process it is contemplated that the wound package of yarn or thread produced will be characterized by considerable density and yet will be uniformly permeable throughout to facilitate any fluid treatment deemed necessary or desirable.

The provision of readily adjustable apparatus for producing wound packages of uniform permeability under either high or low tension is also an object of this invention, while the apparatus is contemplated for use in ordinary bobbin spinning, in two bath spinning or in other winding operations requiring the production of a dense package of uniform permeability.

To this end it is contemplated to continuously

wind packages of yarn according to a predetermined fixed pattern such as the "basket weave" and to relatively displace successively wound portions of the pattern to produce a dense but uniformly permeable wound package.

Other objects and advantages of this invention will be apparent from a consideration of the following detailed description of a preferred embodiment thereof in conjunction with the annexed drawings wherein:

Figure 1 is a schematic perspective view of a portion of a winding machine illustrating an assembly including a gear train for driving the bobbins and traverse mechanism in synchronism, an automatic tripping coupling and a stroke shortening, stroke displacement device operable upon the traverse;

Figure 2 is a view in side elevation of a portion of the traverse mechanism;

Figure 3 is a view taken along line 3-3 of Figure 2;

Figure 4 is a view taken along line 4-4 of Figure 2;

Figure 5 is a view taken along line 5-5 of Figure 2;

Figure 6 is a view in side elevation of the device for shifting the cam shown in Figure 2 to effect shortening of the stroke of the traverse arm;

Figure 7 is a view in front elevation of the device shown in Figure 6;

Figure 8 is a view in rear elevation of the device shown in Figure 6;

Figure 9 is a view in side elevation of the automatic tripping coupling interposed between the driving gear train and the traverse mechanism;

Figure 10 is a view in front elevation of the coupling shown in Figure 9;

Figure 11 is a graphic illustration showing how the principle of the tripping coupling is utilized to produce peripheral displacement of the pattern as the yarn is laid up on the bobbin;

Figure 12 illustrates the peripheral displacement (Figure 11) of the yarn graphically superimposed on the stroke shortening and stroke displacement effected by the mechanism disclosed in Figure 1;

Figure 13 represents a bobbin showing peripheral displacement of the pattern effected by the tripping coupling and the relative positions of the diamond formations circumferentially;

Figure 14 is a longitudinal half-section of the bobbin showing several layers of yarn forming generally conical ends as a result of the stroke shortening and stroke displacement; and

Figure 15 is an end elevation of the bobbin diagrammatically showing an end pattern with peripheral displacement.

Referring to the winding machine shown in Figure 1, it will be seen that a series of yarns 10 issuing from a spinning bath, not shown, are wound on perforated bobbins 11 supported and driven by shafts 12. The yarns 10 are laid up in successive courses, axially of bobbins 11, by a reciprocating traverse bar 13 of conventional form which is driven at a rate of speed directly proportional to the speed of rotation of the bobbins.

To effect this synchronism as regards the operating speeds of traverse bar 13 and bobbins 11, each is driven indirectly from a single source of power, namely gear 14 which is attached to shaft 15 of a variable speed power source not shown.

To effect a driving connection between each

bobbin 11 and gear 14, the respective shafts 12 of bobbins 11 are provided with identical gears 16, gears 16 meshing with identical gears 17 attached at spaced intervals along a shaft 18. Shaft 18 is driven by gear 14 through gear 19 and as a consequence will cause all of the bobbins 11 to rotate in the same direction at a constant speed determined by the speed of rotation of shaft 15 and the relative diameters of gears 14 and 19.

It will be recognized that although only two bobbins are shown in Figure 1, a large number of such bobbins will be employed simultaneously in commercial spinning.

The traverse bar 13 which operates in synchronism with bobbins 11 is also driven from gear 14 although the intermediate driving connections are somewhat more complex. It will be noted that traverse bar 13 is supported at spaced intervals by arms 20 which are attached to and depend from a rocker shaft 21 suitably journaled in a manner not shown. Upon oscillation of rocker shaft 21, arms 20 will also oscillate thus causing traverse bar 13 to reciprocate and thereby lay up yarn 10 in superimposed courses extending axially of each bobbin.

To effect the oscillation of shaft 21 an arm 22 is keyed thereto, this arm being provided with a cam follower 23 movable in response to rotation of a heart-shaped cam 24. Heart cam 24 is mounted for rotation with a shaft 25 which is provided at one end with a driving sprocket 26.

Since the rotation of shaft 25 is imparted to cam 24 which controls the reciprocation of traverse bar 13, shaft 25 is driven from gear 14 through its sprocket 26 in order to bring about the synchronism discussed above. However, it is desirable that the speed of traverse bar 13 be considerably less than, although proportional to, the speed of rotation of bobbins 11 also driven from gear 14. To this end, a speed reduction gear train is interposed between gear 14 and sprocket 26 to reduce the speed of shaft 25 with respect to that of shaft 18.

This gear train consists of gear 27; gear 19; gear 28, identical in size to gear 27; gear 29, smaller than gear 28 (although this is not necessary) and mounted on a shaft 30 therewith; gear 31 larger than gear 29 and sprocket 32 mounted on shaft 33 with gear 31 and connected by chain 34 to sprocket 26. It will be understood that each of the shafts for the various gears is suitably supported in a journal not shown. By rotation of shaft 15, movement will be imparted to shaft 18 through gear 19 and to shaft 25 through gears 27, 28, 29 and 31, and sprockets 32 and 26. Gears 27 and 28 are of equal diameter so that a second series of bobbins may be driven from gear 28 in the same way that bobbins 11 are driven, that is, through a construction similar to gear 19 and shaft 18.

The spinning machine as thus far described, if operated, would cause superimposed courses of yarn to be built up on the bobbins according to a fixed pattern determined by the speed ratio between traverse bar 13 and bobbins 11. Each course of yarn would, however, exactly correspond to every other course in both length and pattern.

In order to displace portions of the pattern with respect to previously wound portions thereof and thereby avoid the occurrence of interstices in radial alignment as well as to build a package having the usual conical ends, stroke shortening and stroke displacement are superimposed upon the pattern wind by adjustment of the eccen-

tricity of the surface of cam 24 with respect to shaft 25 which eccentricity will alter the length of the path of reciprocation of traverse bar 13. To explain the manner in which this is effected, reference is made to the manner of mounting cam 24 on shaft 25 as well as to the means for determining the extent of eccentricity of its surface with respect thereto.

Upon consideration of Figures 2 to 5, inclusive, of the drawings, it will be seen that cam 24 surrounds an arm 35 which is keyed to shaft 25 for rotation therewith. This arm is the driving arm for effecting rotation of cam 24 with shaft 25. However, because of the fact that cam 24 is to be shifted in radial paths with respect to shaft 25, no direct connection between arm 35 and cam 24 is made. In lieu of this, a spider 36 is mounted around shaft 25 adjacent cam 24 and driving connections between the free end of arm 35 and spider 36, and spider 36 and cam 24, are effected. The connection between the free end of arm 35 and spider 36 is a simple one consisting of a threaded bolt 37 passed through each member and held in position by nuts 38 and 39. Inasmuch as spider 36 is subject to radial movement with respect to the axis of bolt 37, a slot 37a is provided in the spider for the bolt. Pairs of bolts 40 and 41 having threaded ends connect spider 36 and cam 24, the latter being provided with elongated slots 42 so that it may be bodily shifted with respect to the bolts. Because of the necessity for shifting the position of cam 24 on the pairs of bolts 40 and 41, nuts cannot be drawn directly against the cam. As a consequence, these bolts are constructed to include polygonal shank portions 43 of such a diameter that the thickened portion will not pass through slots 42. Another spider 44 is mounted on the end of the bolts remote from the ends passing through spider 36, spider 44 being spaced from cam 24 because of the thickened shanks 43 of both pairs of bolts and cam 24 being held against wobbling by the shoulders of the bolts and the smooth surface of spider 36. Nuts 45, engaging the threaded ends of bolts 40 and 41, serve to hold spiders 36 and 44 as well as cam 24 in operating position. Rotation of shaft 25 will thus cause rotation of arm 35 which in turn will cause spider 36 to turn. Spider 44 and cam 24, being attached by bolts 40 and 41 to spider 36, will also turn therewith.

Since cam 24 is movable in a plane at right angles to shaft 25 between the shoulders of bolts 40 and 41 and spider 36, it is evident that the degree of eccentricity of the cam surface with respect to shaft 25 may be varied within limits defined by slots 42. To this end a cam mechanism is associated with cam 24 which, when actuated, will vary the eccentricity of the cam surface with respect to shaft 25.

The cam follower mechanism on cam 24 includes a traverse bar 46 bolted thereto. At right angles to this bar and depending downwardly therefrom is the cam follower proper designated by the numeral 47. A spring mechanism continuously holds follower 47 against a cam 48 which is mounted for rotation in spider 44. It will be borne in mind that cam 24 is movable with respect to spider 44 and bolts 40 and 41. For this reason coil springs 49 are suitably attached at 50 to cam 24 and extend to projections 51 of bolts 40. It will be seen that the effect of these springs is to constantly draw cam 24 downwardly from the position shown in Figure 4. Since cam follower 47 is rigidly attached

to cam 24, constant contact between cam 48 and follower 47 will be maintained.

Cam 48 is attached for rotation with shaft 52 which is journaled at 53 in spider 44. A universal coupling 54 extends from shaft 52 and is adapted for attachment to a driving means. In order to vary the effect of cam 48 upon cam 24, slots 55 are provided in spider 44 for the reception of bolts 40 and 41. The adjusted position of spider 44 with respect to the bolts is determined by operation of set screws 56, lock nuts 57 serving to maintain the adjustment. Adjustment may be made by loosening nuts 45 and when the new position is attained they are simply drawn tight thus again securing spider 44 against the shoulder defined by shank portions 43 of bolts 40 and 41 which in turn are attached to spider 36.

It will be noted that springs 49 urge the cam 24 to a position of maximum eccentricity with regard to shaft 25. As a consequence, cam 48 is so adjusted that at the start of a winding operation the surface closest to the center of shaft 52 is presented for contact by follower 47. Cam 48 is then gradually caused to turn as shown by the arrow in Figure 4, thereby gradually decreasing the degree of relative eccentricity between cam 24 and shaft 25, and thus shortening the stroke of arm 22 and traverse bar 13. This will produce a package having conical ends, because of reduction in the length of successive traversing courses of yarn laid up on bobbin 11.

By referring to Figure 5 of the drawings, it will be seen that the bearing surface around which spider 36, cam 24 and spider 44 turn, is not shaft 25 but hollow cam shaft 58. It is evident that by turning shaft 58 the relative eccentricity of shaft 25 and cam 24 may be varied and that this variation will be superimposed upon the variation produced by movement of cam 48. Thus, by driving cam shaft 58 faster than cam 48 it is possible to produce a stroke displacement as well as a stroke shortening, the displacement, however, being limited by the position of shaft 58.

The manner in which cam shaft 58 is operated is known in the art to which this invention pertains being shown in Patent 2,122,092 to Engel. In Figure 7 of the patent it will be noted that cam 22 is keyed to bushing 23 and rotates about shaft 10. Cam 22 of the patent corresponds to cam shaft 58 of the application, and shaft 10 of the patent corresponds to shaft 25 of the application. Cam 22, in its path of rotation, motivates roller 20, which is bolted to member 13 corresponding to applicant's spider 36.

The means by which the movement of cam 48 is effected is shown in Figures 6 to 8, inclusive. The cam shifting device consists of a disc 59 keyed at 60 to shaft 25. A star gear 61 is attached to disc 59 and is adapted, upon rotation of shaft 25, to strike a stationary pin, not shown. The motion thus imparted to star gear 61 is conveyed through a suitable speed reduction transmission to a shaft 62 which is attached to coupling 54 of shaft 52.

Star gear 61 is attached to shaft 63 which is held in position parallel to the plane of disc 59 by journals 64 and 65 fastened to the disc. A portion of shaft 63 is eccentric and over this portion a pawl 66 is mounted, a collar 67 urged by spring 68 serving to hold pawl 66 in position, abutting journal 64. Pawl 66 cooperates with a ratchet wheel 69 mounted on a shaft 70 provided with journals 71 and 72 suitably fastened to disc 59. In order to hold pawl 66 in constant engage-

ment with ratchet wheel 69 a spring 73 is attached thereto, this spring being fastened to an arm 74 attached to the disc. The ratchet wheel 69, on the other hand, is held in position against reversal by a spring urged pawl 75 attached for pivotal movement to disc 59. It will be recognized that as shaft 25 rotates and star gear 61 strikes the fixed pin disposed in its path, shaft 63 will slowly turn, thereby shifting first downwardly and then upwardly the position of pawl 66, a complete reciprocation of said pawl being effected upon every complete revolution of shaft 63. As pawl 66 moves down it will turn ratchet wheel 69 in a counterclockwise direction thereby imparting movement to shaft 70. Shaft 70 is provided with a worm 75a at its end remote from ratchet wheel 69 and this worm is adapted to drive a transmission consisting of gears 76, 76a, 77 and 78 and thereby effect movement of shaft 62. Gears 76, 76a and 77 are mounted on studs projecting out from disc 59, suitable journals being provided to control axial and radial thrust. Gear 78, on the other hand, is mounted on a shaft 79 which extends through disc 59 and carries a coupling 80 at its other end. Journals 81 and 82 are provided for shaft 79. It will be noted that the stud on which gear 77 is mounted is received in a slot 83 of disc 59. This slot permits the substitution of gears of varying size, thereby permitting adjustment of the speed of rotation of shaft 62 with regard to the speed of rotation of star gear 61.

When the portions of the machine thus far described are put into operation by driving shaft 14, yarn 10 will be wound on bobbins 11 in courses the length of which is dependent upon the operation of cam 48 and cam shaft 58 which in turn control the eccentricity of cam 24. The speed of cam shaft 58 is determined by the speed of shaft 25 and a planetary transmission such as that shown in Figure 7 of the patent to Engel, No. 2,122,092, previously mentioned. One satisfactory adjustment of these cams is effected by setting the gearing on disc 59 to turn cam 48 one complete revolution for every 12,000 revolutions of shaft 25 while cam 58 is turned one complete revolution for every 3.9 revolutions of shaft 25. Bobbins 11 are driven at about 25 revolutions to 3 revolutions of cam 24. The eccentricity of cam shaft 58 is adjusted to about 25 mm. while a total stroke shortening of 50 mm. is effected by cam 48. By this arrangement, a package having conical ends is built, the angle of the cone being determined by cam 48 by its action upon cam 24, while each successive course is axially displaced with respect to the course previously laid up by the action of cam shaft 58. Since cam shaft 58 is operating so much faster than cam 48 it will be recognized that the stroke displacement will recur a large number of times during the preparation of a package. This displacement will, of course, modify the pattern wind produced by driving cam 24 and bobbins 11 in synchronism from a common power source, shaft 15.

To effect a circumferential displacement of successive portions of the wound package an automatic tripping coupling may be interposed between driving gear 14 and cam 24, the effect of this coupling being periodically to stop momentarily the rotation of shaft 25 and hence cam 24 driven therefrom. The apparatus for accomplishing this is shown in Figures 9 and 10 of the annexed drawings. As shown the tripping coupling includes a disc 84 keyed at 85 to shaft 25. 75

disc 84 being provided with an elongated sleeve portion 86 which overlies a short portion of shaft 25. A hollow shaft 87 is mounted for rotation on sleeve 86, this shaft having sprocket 26 and ratchet wheels 88 and 89 keyed thereto. In order to effect the rotation of shaft 25 in response to rotation of shaft 87 carrying driven sprocket 26, a clutch mechanism is interposed between ratchet wheel 89 and disc 84.

10 The driving of disc 84 from ratchet wheel 89 is effected by the employment of two pawls 90 pivotally attached to the disc at 91 and urged into engagement with ratchet wheel 89 by springs 92 attached to an arm 93 attached to and extending out from the disc. It will be noted that the pawls are so arranged that only one pawl 90 at a time is driven by ratchet wheel 89, the remaining pawl being but partially inserted into an adjacent ratchet of the wheel. It is therefore evident that by moving the driven pawl out of engagement with ratchet wheel 89, said sprocket will turn without moving disc 84 until the other pawl abuts the driving edge of the tooth in which it was previously only partly received. During 15 this period the rotation of shaft 25 will cease. To effect intermittently the alternate displacement of pawls 90 a star gear 94 is employed, this gear driving through a transmission a disc 95 on opposite sides of which are mounted pawl displacing pins 96 and 97 each pin acting on its respective pawl.

20 Star gear 94 is mounted on shaft 95a which is attached to disc 84 through journal 96a. The end of shaft 95a remote from star gear 94 has attached thereto a worm 97a. This worm meshes with gear 98 mounted on shaft 99, said shaft also carrying gear 100. Gear 100 meshes with gear 101 mounted on shaft 102 and gear 101 meshes with gear 103 mounted on shaft 104. The disc 25 95, carrying pins 96 and 97, is also mounted on shaft 104 and is driven thereby.

25 The gear train comprising gears 97a, 98, 100, 101 and 103 is set in motion by star gear 94. A pin, not shown is disposed in the path of this gear as it turns bodily with disc 84 and upon striking this pin, gear 94 is moved. After a number of revolutions of shaft 95a determined by the diameters of the various gears in the transmission, one of the pins 96 or 97 will displace its 30 pawl 90 thereby causing disc 84, and hence shaft 25, to stop. A pawl 106 is also attached to disc 84 by pivotal connection to post 105. This pawl engages sprocket wheel 88 and merely functions to keep shaft 25 and disc 84 from turning ahead 35 of the driving member 89.

40 The tripping coupling described above, when placed in operation, will cause momentary intermittent cessation of movement on the part of shaft 25. On the other hand, because of the 45 position of the tripping coupling the driving of bobbins 11 will continue uninterrupted. The result, therefore, of momentarily stopping the rotation of shaft 25, and consequently heart cam 24, is to interrupt the synchronism of the bobbins with the traverse bar 13 driven from cam 24. Inasmuch as a pattern wind is being produced by the driving synchronism, it will be seen that the momentary cessation of movement on the part of the traverse arm will result in circumferential displacement or angular displacement in a plane normal to the axis of the spool of succeeding portions of the pattern produced with respect to previously wound portions thereof.

50 55 In operating the machine shown in Figure 1,

it is possible to produce a pattern wind and to modify the production of the pattern in three ways. The pattern may be displaced only circumferentially by the employment of the tripping coupling alone without the use of hollow cam shaft 58 which effects a stroke displacement; the stroke shortening mechanism, however, may be used to effect the production of a package having conical ends. On the other hand, the pin driving star gear 94 may be removed and the cam shaft 58 may be brought into operation. This will result solely in a stroke displacement which will, of course, result in modifying the formation of the pattern produced by the driving of the traverse bar and bobbins in synchronism. Still further relative displacement of the successively wound portions of the pattern may be effected by the use of the automatic tripping coupling in conjunction with stroke shortening and stroke displacement.

In other words, according to this invention, yarn is laid up in successive courses on bobbins 11, the production of the courses following a pre-determined pattern dependent upon the speed ratio between traverse bar 13 and bobbins 11. The formation of the pattern may be modified by stroke displacement and/or stroke shortening, and/or portions of the pattern per se may be displaced circumferentially. In any instance, it is customary to superimpose the pattern displacement upon ordinary stroke shortening employed in making a package having conical ends.

The term "course" as employed in the specification and claims is intended to define the laying up of yarn axially of the rotating bobbin for a distance determined by the length of the stroke of the traverse bar.

The term "pattern" as used herein means the orderly diamond arrangement throughout the cross-wound package and results from maintaining a constant ratio between the speed of the traverse mechanism and the speed of rotation of the bobbins. Therefore, the pattern is pre-determined and fixed although its formation may be modified by stroke shortening and/or stroke displacement. This synchronous cross-winding causes an orderly arrangement of the diamond formation throughout the body of the package and is, therefore, properly termed the "pattern." When packages are wound by mechanisms involving separate drives for the traverse and the bobbin, no pattern formation is effected as the arrangement of the diamonds is haphazard and occur in a random manner throughout the body of the package.

Having now described the invention in its preferred form, it is understood that variations and modifications may be made therein without departing from the spirit of the invention, and it is desired that the scope thereof be limited only by the spirit of the appended claims.

What is claimed is:

1. In apparatus for winding yarn in package form, a bobbin, a traverse mechanism, means for driving said bobbin and traverse mechanism in synchronism to produce a pattern wind, and means for circumferentially displacing successively wound portions of the pattern, whereby to produce a substantially dense package of yarn having superior washing qualities.

2. In apparatus for winding yarn in package form, a bobbin, a traverse mechanism, means for driving said bobbin and traverse mechanism in synchronism to produce a pattern wind, means for successively shortening and lengthening the

stroke of the traverse mechanism a plurality of times during the winding of a single package, means for continuously reducing the average length of the stroke of the traverse mechanism during the preparation of the package, and means for effecting circumferential displacement of successive portions of the pattern.

3. In apparatus for winding yarn in package form, a bobbin, a traverse mechanism, means for driving said bobbin and traverse mechanism in synchronism to produce a pattern wind, means associated with the traverse mechanism for controlling the shape of the package and means for periodically momentarily stopping movement of one of the driven elements to effect relative displacement of successive portions of the pattern.

4. In apparatus for winding yarn in package form, a bobbin, a traverse mechanism, means for driving said bobbin and traverse mechanism in synchronism, means for continuously shortening the stroke of the traverse mechanism during the winding period and means intermediate the driving means and the traverse mechanism for periodically momentarily stopping movement of the latter, whereby to produce a wound package having superior washing qualities.

5. In apparatus for winding yarn in package form, a bobbin, a traverse mechanism, means for driving said bobbin and traverse mechanism in synchronism, means associated with the traverse mechanism for controlling the shape of the package, separate means associated with said traverse mechanism for effecting displacements of the stroke of said traverse mechanism within limits defined by said controlling means, and means for periodically momentarily stopping movement of said traverse mechanism, whereby to produce a substantially dense package of yarn having superior washing qualities.

6. In apparatus for winding yarn in package form, a bobbin, a traverse mechanism, means for driving said bobbin and traverse mechanism in synchronism, means for successively shortening and lengthening the stroke of the traverse mechanism a plurality of times during the winding of a single package, means for continuously reducing the average length of the stroke of the traverse mechanism during the preparation of the package, and means intermediate the driving means and the traverse mechanism for periodically momentarily stopping movement of the latter, whereby to produce a substantially dense package of yarn having superior washing qualities.

7. In apparatus for winding yarn in package form, a bobbin, a mechanism including a cam and a traverse bar driven thereby, means for driving said bobbin and cam in synchronism, means associated with the cam for determining the shape of the package and means intermediate said driving means and said cam for periodically momentarily stopping the movement of the latter.

8. In apparatus for winding yarn in package form, a bobbin, a mechanism including a cam and a traverse bar driven thereby, means for driving said bobbin and cam, means associated with the cam for determining the shape of the package and means intermediate said driving means and said cam for periodically momentarily stopping the movement of the latter.

9. A process for producing cross-wound packages of yarn or the like comprising, continuously winding successive courses of yarn accord-

ing to a fixed pattern and intermittently, relatively circumferentially displacing successively wound portions of the pattern.

10. In apparatus for winding yarn in package form, a bobbin, a traverse mechanism, a driven shaft for driving the bobbin, means for driving said traverse mechanism in synchronism with said driven shaft to produce a pattern wind and means for periodically momentarily stopping movement of one of the driven elements to effect

relative displacement of successive portions of the pattern.

11. A process for producing cross-wound packages of yarn or the like which comprises continuously winding successive courses of yarn according to a predetermined pattern, modifying the formation of the pattern and intermittently, relatively, circumferentially displacing successively wound portions of the pattern.

ARTHUR L. JACKSON.
